United States Patent Office

Des. 226,844
Patented May 8, 1973

226,844

PALLET

Theodor M. Box, 1108 Aileen Road, Brielle, N.J.

Filed Oct. 22, 1971, Ser. No. 191,965

Term of patent 14 years

Int. Cl. D12—99

U.S. Cl. D14—3 N

Fig. 1.

Fig. 2.

FIG. 1 is a top perspective view of a pallet showing my new design;

FIG. 2 is a side elevation view thereof;

FIG. 3 is a top plan view of the pallet; and

FIG. 4 is a bottom plan view of the pallet.

I claim:

The ornamental design for a pallet, as shown.
